KEY RING

Francois U. Dumas, Spencer, Mass.

Application January 5, 1951, Serial No. 13,687

Term of patent 3½ years

(Cl. D17—14)

To all whom it may concern:

Be it known that I, Francois U. Dumas, a citizen of the United States, residing at Spencer, in the county of Worcester, and State of Massachusetts, have invented a new, original and ornamental Design for a Key Ring of which the following is a specification, reference being had to the accompanying drawing forming part thereof.

Fig. 1 is a view in front elevation; and

Fig. 2 is a view in side elevation of a key ring showing my new design.

I claim:

The ornamental design for a key ring, as shown.
FRANCOIS U. DUMAS.
